UNITED STATES PATENT OFFICE

2,189,450

CRACKER OR WAFER HOLDER

William E. Robinson, Taft, Calif.

Application February 6, 1939, Serial No. 254,848

4 Claims. (Cl. 65—15)

This invention is a device for holding rectangular crackers, wafers, confections and various other food products in a vertical position as to their side faces, that is, having means for supporting the articles on bottom edges diverging from a lower corner at the bottom of a vertical diagonal.

5 It is an object to provide a more or less individual service, wafer-like food holder in which 10 a considerable number of the wafers are stood face to face in a horizontal row.

A further object of the invention is to provide 15 a wafer holder which is of very simple structure, of low cost of manufacture and therefore sale price, which is free of functionally movable parts, and is substantial and is easily kept in a clean and attractive condition.

A further object of the invention is to provide 20 a simple and practical method for the ready manufacture of the holder.

The invention consists of certain advancements in this art as set forth in the ensuing disclosure and having, with the above, additional objects and advantages as hereinafter developed, and whose 25 construction, combinations and details of means, and the manner of operation will be made manifest in the description of the herewith illustrative embodiment; it being understood that modifications, variations and adaptations may be within 30 the spirit, scope and principle of the invention as it is hereinafter more directly claimed.

Figure 1 is a perspective of the holder.

Figure 2 is an end elevation of the holder, with an applied cracker standing thereon.

35 The holder incorporates a stabilizing, elongate, narrow and suitably deep base 2 of metal, wood or other suitable material, and having a central, longitudinal, preferably V-shaped channel 3, here from end to end of the base.

40 Into this channel 3 there is reposed a complementary corner angle 4 of a preferably rectangular-section trough 5 having a length about equal to that of the base 2; the trough being of any suitable material which may be easily kept clean.

45 The trough 5 is suitably affixed to the walls of the channel 3, as by small brads, nails or screws 6 passing into the base 2, though it may be otherwise joined to the base if so desired.

50 Adjacent to each end of the trough 5 its walls are perforated at 7—7 in opposite manner to receive respective ends of a pair of wafer face sup-

ports in the form of wire bails 8—8 which have end hooks 9—9 to be passed through and inter hooked with the holes 7—7, though these ends supports 8—8 may be of other form and means of attachment.

5 Figure 2 shows an end view of the holder with a square cracker or wafer C standing on one corner in the trough and being sustained and positionally arranged by the trough walls engaging and forming means to receive the bottom edges of the square cracker. It will be understood that a 10 row of crackers laid face to face will be kept upright between and by the end supports or bails 8—8.

The bails form effective handles by which the 15 holder may be carried, or shifted from place to place on a service table.

What is claimed is:

1. A wafer or the like holder comprising a 20 stabilizing base, upwardly divergent, longitudinal side walls, which are of about equal height and join in an inverted apex, affixed to the top of the base and form an elongate trough to support 25 facially adjacent wafers stood, with diagonals vertical, in a row in the trough; said base having a central V-channel to receive the inverted apex of the trough.

2. The holder of claim 1, and in which said 30 trough is secured to the said base by fasteners driven thereto through the apex into the base at the said channel.

3. The holder comprising a stabilizing base, upwardly divergent side walls affixed to the top of the base and forming an elongate trough along the base, and transverse end elements across the 35 trough to support the faces of adjacent wafers stood vertically in a row in the trough, and in which the transverse elements are in the form of bails having their ends interhooked in the end portions of the said walls.

4. A wafer or the like holder comprising a 40 stabilizing base of elongate form having a V-section channel along its top, a V-shaped trough of sheet form material having a bottom angle complementary to the channel and set therein, and means joining the bottom of the trough through the angle to the base, the trough having transverse wafer supports in the form of handle loops at its ends.
